BUNK BED

Oliver W. Masterson, Glenview, Ill., assignor to The Norwood Manufacturing Company, Chicago, Ill., a corporation of Ohio

Application April 5, 1955, Serial No. 35,368

Term of patent 14 years

(Cl. D5—4)

Fig. 1.

Fig. 2.

Fig. 3.

Fig. 4.

Fig. 1 is a perspective view of a bunk bed embodying my new design;

Fig. 2 is an elevational view of an end panel forming part of the same, and

Figs. 3 and 4 are sectional views taken respectively along the lines 3—3 and 4—4 of Fig. 2.

The characteristic features of the design reside in the portions shown in full lines.

I claim:

The ornamental design for a bunk bed as shown and described.
